UNITED STATES PATENT OFFICE.

PEARL BORDEAUX, OF MOUNT DESERT, MAINE.

DEVICE FOR FACILITATING THE REMOVAL OF VALVES.

1,334,131.

Specification of Letters Patent. Patented Mar. 16, 1920.

Application filed January 27, 1919. Serial No. 273,360.

To all whom it may concern:

Be known that I, PEARL BORDEAUX, a citizen of the United States, and a resident of Mount Desert, in the county of Hancock 5 and State of Maine, have invented certain new and useful Improvements in Devices for Facilitating the Removal of Valves; and I do hereby declare the following to be a full, clear, and exact description of the 10 invention, such as will enable others skilled in the art to which it appertains to make and use the same.

This invention relates to improvements in devices for facilitating the removal of 15 valves,—the object of the invention being to provide an efficient tool whereby the valve spring may be compressed and the easy removal of the spring-retaining pin permitted prior to the removal of the valve and 20 its cage.

With this object in view, the invention consists in certain novel features of construction and combinations of parts as hereinafter set forth and pointed out in the 25 claims.

In the accompanying drawings, Figure 1 is a view showing the application of my invention; Fig. 2 is an elevation reverse to that shown in Fig. 1; Fig. 3 is a longitudinal 30 sectional view; Fig. 4 is a transverse section on the line 4—4 of Fig. 1, and Fig. 5 is a detail view of the slide 5 and movable jaw 7.

1 represents a metal block provided at one 35 end with a jaw 2 having a recess 3 in its inner face. The block 1 is recessed and provided with overhanging flanges 4 to form guides for a slide 5, the latter having flanges 6 to move under the flanges 4. The slide 5 is formed with a jaw 7 to coöperate with the 40 jaw 2 and form a clamp. The jaw 7 is made with a recess 8 in its inner face which coöperates with the recess 3 of the jaw 2 to receive the stem of a valve. A thumb screw 9 45 passes through and is swiveled to the jaw 7 and enters a threaded socket 10 in the jaw 2 or in the block 1 rearwardly of the jaw 2 for the purpose of moving the slide 5 and its jaw 7 to clamp the jaws on the valve 50 stem or removing the device from the latter.

A bar 11 having a slot 12, is mounted to slide on the block 1 and is guided in its movements by a flanged lug 13 made rigid 55 with the block 1. The slotted bar 11 is of sufficient length to extend beyond both ends

of the block 1 and beyond the jaws 2—7, and at its lower end, said bar is provided with two lateral fingers or jaws 14 between which the jaws 2—7 may move.

The upper end of the bar 11 is provided with a lateral arm 15 which projects over the upper end of the block 1 and in this arm a thumb nut 16 is swiveled. A screw 17, made rigid with the block 1 and projecting 60 upwardly therefrom is threaded through the thumb nut 16, so that when the latter is turned, the bar 11 will be moved relatively to the block 1.

In the operation of the device, the same is 70 placed over the valve stem 18 and the jaws 2—7 clamped thereto, the fingers or jaws 14 resting on the disk 19 against which the valve spring 20 bears. The operator will now turn the thumb nut 16 to cause the 75 bar 11 to move downwardly thus causing the disk 19 to move away from the spring-retaining pin 21 and the valve spring 20 to be compressed. The operator may now easily remove the spring-retaining pin 21 80 and after detaching the device from the valve stem, the disk 19 and valve spring 20 may be removed.

The valve, its stem and cage may now be 85 withdrawn with the use of another tool.

Slight changes might be made in the details of construction of my invention without departing from the spirit thereof or limiting its scope and hence I do not wish to restrict myself to the precise details herein 90 set forth except as required by the scope of the claims.

Having fully described my invention what I claim as new and desire to secure by Letters-Patent, is:

1. In a device of the character described, the combination with a block provided at one end with clamping jaws for engaging the stem of a valve, of a bar mounted on said block and having means at its end adjacent to said jaws for engaging the abutment of the valve spring, and means for moving said bar relatively to said block and the jaws carried by the latter for compressing the said spring.

2. In a device of the character described, the combination with a block and clamping jaws at one end thereof for engaging stem of a valve, of a bar mounted to slide on said block and having fingers at one end receiving said jaws between them, the said fingers to engage the abutment on the valve stem

against which the valve spring bears, and means for moving said bar and its fingers in a direction to compress the said spring.

3. In a device of the character described, 5 the combination with a block provided at one end with a fixed jaw, a slide mounted on said block and provided with a jaw to co-operate with said first-mentioned jaw, a manually operable screw for moving one of 10 said jaws relatively to the other, a slotted bar mounted on said block, a guide lug for said bar, spaced fingers at one end of said

bar receiving said jaws between them, a lateral arm at the other end of said bar, a nut swiveled to said lateral arm, and a screw 15 rigid with the block and passing through said swiveled nut.

In testimony whereof I have signed this specification in the presence of two subscribing witnesses.

PEARL BORDEAUX.
